Dwight Thompson
ATTORNEYS.

UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

SIGNALING DEVICE.

Application filed December 27, 1922. Serial No. 609,333.

This invention relates to certain new and useful improvements in signaling devices, and is closely related to my co-pending applications Serial No. 396,802, filed July 16, 5 1920, and Serial No. 493,498, filed August 18, 1921.

The main object of the invention is the production of a signaling device of the motor-driven type, in which accurate adjustment to a substantially pre-determined extent is readily made, either to compensate for wear or to effect the desired position of the diaphragm-actuated member with reference to the diaphragm to effect such vibration of the latter as will result in the production of a satisfactory signal for the purpose at hand.

Another object is the production of a device of the character described in which the parts are normally so held in any position of adjustment as to prevent rattling or chattering of the same under ordinary conditions of use.

Other objects and advantages relate to the 25 details of construction of the apparatus and the parts thereof, all as will more fully appear from the following description, taken in connection with the accompanying drawings, in which:

Figure 1 is a longitudinal sectional view 30 of a device of my invention.

Figure 2 is an end view of the adjusting means.

Figure 3 is a sectional view on line 3—3, 35 Figure 2.

The horn structure may be of various form and character in so far as the ordinary elements thereof are concerned, including the amplifier —1—, the front diaphragm case section —2—, the rear diaphragm case section —3— which, as shown, is of dished or cup-shaped form, the diaphragm —4—, the motor case —5—, which as illustrated, is of U-shaped form with its threaded ends 40 —6— and —7— penetrating and projecting through the base of the diaphragm section —3— and secured in place in any suitable way, as by the nuts illustrated.

The structure further involves the usual 50 armature —8—, armature shaft —9— journaled in the cross bar —10— of the U-shaped case and in the base of the diaphragm case section —3—. This shaft is provided with a commutator —11— for sliding engage-

ment with the brushes —12— supported 55 from the U-shaped case section.

The structure so far described is substantially that disclosed in the applications above referred to.

The specific features of the invention here 60 reside, as above stated, in the means for positioning and maintaining the armature shaft —9— in proper adjustment without possibility of rattling or chattering of the cam —13— against the diaphragm projection —14— during ordinary conditions when the structure is not operating. The armature shaft is normally pressed rearwardly by means of a spring member —15— which bears against the forward end of the shaft 70 and has its end portion mounted on the projecting end as by one of the side walls of the U-shaped case —5—, and being held in position between the case section —3— and the adjusting nut —16—.

For the purpose of effecting movement of the shaft —9— and for holding it tightly against the spring —15— there is provided a rear bearing consisting of an adjusting bar —17— which, as illustrated, has its main 80 portion extending substantially parallel with the cross bar —10— of the case —5—, and upon one side of the shaft —9— the cross bar —10— is provided with an opening or slot —18— for receiving the flange —19— formed upon one end of the bar —17—, such engagement of the parts preventing movement of the bar —17— except in a direction toward and from the cross bar —10— and for the purpose of effecting such movement 90 there is provided a threaded stud —20— positioned upon the opposite side of the shaft —9— from the opening —18—, such stud having a threaded engagement with the cross bar —10— and extending through the 95 adjusting bar —17— and having its head in contact with said adjusting bar for moving the same toward the cross bar —10—, when the stud is rotated in one direction or permitting movement of the adjusting bar 100 —17— away from the cross bar —10— upon rotation of the stud —20— in the opposite direction, such latter movement being effected by a spring —21— mounted upon the stud —20— and positioned between the cross bar —10— and the adjusting bar —17—.

At a point intermediate the flange —19— and the stud —20— the end of the armature

shaft —9— comes into contact with the adjusting bar —17—. In operation this adjusting bar actuated and constructed as described in connection with the spring —15— 5 holds the shaft —9— under tension in proper adjusted position. An oiling pad —22— may be mounted upon the end of the armature shaft —9—, if desired. Preferably the surface of the head of the stud —20— that 10 comes in contact with the outer surface of the adjusting bar —17— is formed with a series of alternate V-shaped projections and recesses for engagement with alternate V-shaped surfaces and recesses formed in the 15 co-acting surface of the adjusting bar —17— so that a pre-determined adjustment of a very sensitive character can be made by turning the stud one or more notches as may be desired. 20 Altho I have shown a specific construction as illustrative of an embodiment of my invention, I do not desire to limit myself to the details of form, construction or arrangement, except as the same may be specifically 25 required in the claims hereto appended.

I claim:

1. An apparatus of the character described comprising a case section, a shaft journaled in said case section, and means for 30 adjusting said shaft comprising an adjusting bar at the rear of said case section and having a portion in contact with the end of said shaft, a flange on said adjusting bar engaged with the case section at one side of 35 said shaft, a rotary adjusting member engaged with the adjusting bar and having a threaded engagement with the case section on the side of said shaft opposite said flange, and a spring interposed between the adjusting 40 bar and the case section.
2. An apparatus of the character described comprising a case section, a shaft journaled in said case section, means for adjusting said shaft comprising an adjusting 45 bar at the rear of said case section and having a portion in contact with the end of said shaft, a flange on said adjusting bar engaged with the case section at one side of said shaft, a rotary adjusting member engaged 50 with the adjusting bar and having a threaded engagement with the case section on the side of said shaft opposite said flange, a

spring interposed between the adjusting bar and the case section, said rotary member formed with a series of teeth, and means cooperating with said teeth for normally frictionally locking the rotary member in any position of adjustment while permitting a step by step movement of said rotary member to effect adjustment of said shaft. 55 60

3. An apparatus of the character described comprising a case section, a shaft journaled in said case section, means for adjusting said shaft comprising an adjusting bar at the rear of said case section and having a portion in contact with the end of said shaft, a flange on said adjusting bar engaged with the case section at one side of said shaft, a rotary adjusting member engaged with the adjusting bar and having a threaded engagement with the case section on the side of said shaft opposite said flange, and a casing enclosing the case section, shaft and adjusting bar, and having an opening through which the rotary member extends 75 to permit rotation of said rotary member without removing the casing. 80

4. An apparatus of the character described comprising a case section, a shaft journaled in said case section, means for adjusting said shaft comprising an adjusting bar at the rear of said case section and having a portion in contact with the end of said shaft, a flange on said adjusting bar engaged with the case section at one side of said shaft, a rotary adjusting member engaged with the adjusting bar and having a threaded engagement with the case section on the side of said shaft opposite said flange, a spring interposed between the adjusting bar and the case 85 section, said rotary member formed with a series of teeth, means cooperating with said teeth for normally frictionally locking the rotary member in any position of adjustment while permitting a step by step movement of said rotary member to effect adjustment of said shaft, and a casing enclosing the case section, shaft and adjusting bar and having an opening through which the rotary member extends to permit rotation of said 90 rotary member without removing the casing. 95 100

In witness whereof I have hereunto set my hand this 8th day of December 1922.

WILLIAM SPARKS.
